APPARATUS FOR PRODUCING BAGS

Thomas E. Piazze, Milwaukee, and Roy E. Hanson, Wauwatosa, Wis., assignors, by mesne assignments to Simplex Wrapping Machine Co., Oakland, Calif., a corporation of California

Application September 12, 1938, Serial No. 229,472

5 Claims. (Cl. 93—18)

Our invention relates generally to improvements in the art of producing containers, and relates particularly to an improved bag and to a method of and apparatus for manufacturing the same.

Generally defined, an object of the invention is to provide a new and useful bag structure, and an improved method of and apparatus for manufacturing such structure from sheet material such as regenerated cellulose film.

In the manufacture of bags from cellulose film or other similar sheet material, considerable difficulty has heretofore been encountered in producing a tight closure for the bottom of each bag. In some of the prior bags of this type, adhesive such as cement is used to form the longitudinal seams and the transverse bottom seams, while in others the seams are formed by heating the overlapped portions of the sheet material to cause the coating surface coatings to melt and fuse together. When cement is used, it is impossible with the present commercial methods to form an airtight and moisture proof bag from tubular stock, because the adhesive cannot be applied between the front and rear walls before the bottom closure fold is made, and for this reason the bottom fold is ordinarily formed with one wall extending beyond the other so as to provide a projecting tongue and to permit cementing of both walls of the fold to the adjacent wall of the bag, independently of the other. This usually produces a bag which is not airtight at the bottom because it has slight openings at the ends of the bottom fold. When heat sealing is used, the bottom fold is ordinarily formed and sealed as in the cemented type of bag, or else the bottom fold is cut straight across and folded and subsequently heat sealed by applying pressure and heat to the four superimposed layers of stock. This latter procedure results in the production of bags having diminished holding capacity, because the lower ends of the front and rear walls have been sealed or attached to each other within the bag enclosure and above the fold line.

It is therefore one of the primary objects of this invention to provide an improved bag formed of cellulose film or similar sheet material and an improved method of making the same, wherein the bottom fold may be secured in place and sealed to provide an airtight closure, without providing a tongue or wall extension on the fold, and without destroying or minimizing the holding capacity of the bag.

In the manufacture of bags of this general

type, a ribbon of stock derived from a supply roll, is usually folded longitudinally into tubular formation, and the overlapped edges are then secured to each other to produce a permanent tube which is subsequently cut into the desired lengths each of which is finally closed at one end to form a complete bag. When a large number of these bags of the same size are required, it is customary to operate the bag forming machine continuously and at high speed, and the completed bags are stacked into rather compressed bundles preparatory to delivering, shipping or storing. Because the sheet material becomes rather brittle with age and when subjected to varying atmospheric conditions, sharp creasing at the opposite sides of the bags frequently causes them to tear at the creases and seams, when the bag are distended during loading, thereby entailing considerable waste and loss to the user. The user of such bags may also desire to frequently vary the sizes of the receptacles for different uses, and may only require a relatively small number of one size and larger quantities of other sizes, thus making it desirable for such a user to produce his own bags in the various required shapes and sizes. Production by the user also assures him of obtaining fresh bags, and eliminates the necessity of stacking and storing the containers in compressed bundles which tend to disrupt the seams and to produce sharp creases. In order to insure most economical production of such bags by individual producers, the use of adhesive should preferably be dispensed with, while at the same time permitting the producer to provide tight joints. If such procedure is made possible, the individual bag producer will be in a position to purchase rolls of the bag stock, printed or otherwise decorated in any desired manner, and he may thereafter manufacture bags of any desired size and shape as they are needed.

It is therefore another primary object of this invention to provide an improved method of and apparatus for making bags from a roll of sheet material and in varied amounts and sizes, either plain or decorated, but in a most economical manner.

Some of the more specific objects of our present invention may be enumerated as follows:

To provide a simple and efficient method of making bag-like containers from a continuous ribbon of sheet material such as regenerated cellulose film, and without necessarily utilizing cement to produce tight seams.

To provide an improved machine for rapidly and economically manufacturing bags of various sizes and shapes, with minimum waste of material.

To provide an improved bag which is airtight and moisture-proof at the bottom, and wherein the bottom fold is of uniform thickness and has its several plies firmly attached to each other and to an adjacent wall of the bag without destroying the holding capacity of the bag above the bottom fold.

To provide an improved bag structure formed of regenerated cellulose film and having the seams thereof heat sealed and crimped to produce an airtight container which may be readily and economically manufactured from a continuous ribbon of sheet material.

To provide an improved machine adapted to produce a succession of bags from a continuous ribbon of predecorated or printed sheet material, and having means for insuring proper location of the decorations or printing on the individual completed bags.

To provide an improved bag producing machine which may be manufactured and sold at moderate cost, and which will permit the user to produce either large or small quantities of bags of different sizes and shapes in a most expeditious manner.

These and other objects and advantages of the invention will be apparent from the following detailed description.

A clear conception of several types of the improved bags, and of the several steps of the improved method of constructing such bags, and of the details of construction and operation of one type of machine which may be used in the exploitation of our improved method, may be had by referring to the drawings accompanying and forming a part of this specification wherein like reference characters designate the same or similar parts in the various views.

Fig. 23 is a similar diagram showing the mode of clamping and of advancing the completely sealed bag after bottom closure thereof.

While our invention has been illustrated and described herein as being primarily applicable to a method and apparatus for forming rectangular bags from a ribbon of cellulose film, it is not the intent to thereby unnecessarily limit the scope, since some of the novel features are adapted to be more generally applied in the manufacture of different types of bags from different kinds of material having characteristics simulating that of cellulose material. The use of specific terms for descriptive purposes, is not to be construed as an unnecessary limitation, and is resorted to merely in order to clearly describe the invention and to make the same known to others skilled in the art.

Since the improved bag assemblage is an important feature of our present invention, it appears desirable to initially describe the several bags manufactured in accordance with the present invention and which are illustrated in Figs. 11 to 16 inclusive.

Referring first to Figs. 11 to 13, we show there-in a form of bag embodying the invention which comprises a tubular body 52 having front and rear portions 85 and 86, respectively, and one end of which has been closed by folding over the end part 88 upon the body or wall 86 of the bag along the fold line 89. The several plies of the end part 88 above the fold line 89 are secured together and to the wall 86 of the bag. More particularly, according to the improved method, the bag ma-

terial is first formed into a tube from a supply of sheet material preferably in roll form by bringing the side edges of the sheet into overlapping relation and heat sealing them together by the application of heat and pressure with a longitudinal seam 87, and then the open end of the tube is bent back upon itself at the fold line 89, and the adjacent end plies of the tube are sealed together and to the wall 86 of the tube by crimping 90 and by the simultaneous application of heat or adhesive as will be subsequently explained. While the body has been particularly referred to as having walls, it will be understood that these walls are not necessarily formed by definite fold lines made in the material.

The bag structure shown in Figs. 14 to 16 is substantially similar to that above described except that instead of a plain tube, the side portions of the sheet are creased to provide accordion or bellows portions 93. Otherwise, the structure of the bag and the method of its manufacture is identical with the first form. In this form the tube 52' has front and rear walls 91, 92, a longitudinal seam 94, and a bottom including the end part 95 folded over the wall 92 along a fold line 96 and attached to this wall by crimping 97 and by the application of heat or adhesive as will be subsequently described.

Referring to Figs. 1 to 10 inclusive, we have illustrated therein one type of manually operable improved mechanism for facilitating commercial exploitation of our improved method of producing the improved bag structures of Figs. 11 to 16 inclusive, from regenerated cellulose film provided with a fusible coating. This improved machine or mechanism comprises in general a main elongated frame 25 having at one end thereof, journals 26 adapted to support a supply roll 27 of the stock or sheet material; brake mechanism 28 cooperable with the supply roll 27 to frictionally retard the rotation thereof; guide rollers 29, 30 journaled in the frame 25 for conducting the ribbon 31 of sheet material from the roll 27 in the desired direction; a stationary former plate 32 providing a fixed elongated table secured to the frame 25 and adapted to convert the ribbon 31 into tubular form with overlapped edge portions as it is advanced along the frame away from the supply roll 27; longitudinal seaming structure including laterally spaced folding rollers 33' and a heated and peripherally grooved intervening roller 33 rotatably suspended from an oscillatory arm 34, and coacting through the overlapped edge portions of the ribbon with parallel rods 35 secured to the former plate 32 by means of a block 36; a fixed lower support 37 coacting through the intervening ribbon 31 with the lower face of the former plate 32, and having a flexible ended stripper plate 38 movable longitudinally therebeneath; a lower horizontal resiliently supported cutter blade or knife 39 cooperable with an upper downwardly movable cutter blade or knife 40 to sever the tubular ribbon 31 into predetermined lengths; a carriage 41 supporting bag clamping mechanism and suspending the same for reciprocation along parallel side rails 42 fixed to the frame 25, and along which the carriage retaining guides 43 are adapted to travel; bag end folding structure including a tucker or folding member 44 mounted for oscillation above the delivery end of the former plate 32, and a combined folding and gripping jaw 45 which is swingably mounted upon the carriage 41 and is cooperable with the member 44 to hold the free end portion of the successive lengths of

stock tube over the upper longitudinally seamed wall thereof; a heated vertically reciprocable end crimping plunger element 46 movably suspended from the frame 25 and being cooperable through the folded bag ends and adjacent upper walls with corrugations 47 in the extreme end of the former plate 32; a resilient lower gripper jaw or plate 48 coacting with the swingable jaw 45 to grip the folded end of the tube preparatory to feeding the stock along the frame 25; a carriage and jaw manipulating handle 49 for reciprocating the carriage 41 and the knife 40 and coacting at its upper portion with adjustable stops 50 carried by pivoted elongated side bars 51 in order to predetermine the length of the final bags 52; and mechanism for effecting adjustment of the bars 51 and stops 50 so as to properly position printed or decorative matter on the successive bags 52.

The main frame 25 may be of any desired rigid construction, and the former plate 32, rails 42 and bars 51 should be of sufficient length to permit the manufacture of bags 52 of maximum predetermined lengths; and the printing or decorative matter which is applied to the stock of the roll 27 before the latter is placed in the bag forming machine should also be properly spaced so that it will ordinarily be located in approximately the desired position on the completed bags 52. The action of the former plate 32 and rollers 33' is well known to those skilled in the art, and when the ribbon 31 is converted into tubular formation, the succeeding portion of the plate 32 is confined within the tube. The structure of the longitudinal seaming mechanism is shown in detail in Figs. 4 and 5, and it is to be noted that the roller 33 may be electrically or otherwise heated, and that the continuous circumferential peripheral grooves 53 of this roller are cooperable with the parallel crimping rods 35 only when the ribbon 31 is being longitudinally advanced. The ribs or rods 35 may be spaced from the former plate 32 as shown in Fig. 5 in order to provide flexibility and compensate for irregularities in stock, but these rods may be replaced by rigid ribs reacting against the plate 32. When the ribbon 31 is at rest, the heated roller 33 should be removed from contact therewith as shown in Fig. 1, in order to avoid scorching or burning the stock, and the roller 33 is therefore automatically elevated by means of the side bars 51 which are swingably attached to the frame 25 by pivots 54 and coat with lateral projections 55 on levers 56 which in turn are rigidly attached to pins 57 to which the roller supporting arm 34 is secured. The pins 57 are journaled in fixed brackets 58 secured to and forming part of the frame 25, and obviously, whenever the side bars 51 are elevated by swinging the handle 49 forwardly during clamping as in Fig. 1, the seaming roller 33 will be elevated; whereas a rearward pull on the handle 49 as when stock is being fed along the former plate 32, will cause the roller 33 to gravitate into active or seaming position as in Fig. 2.

The lower cutter blade for knife 39 is resiliently supported for horizontal movement relative to the frame 25 by means of several compression springs 59 as shown in Figs. 8 and 9, and this blade has a slightly inclined cutting edge with which the inclined cutting edge of the downwardly movable blade 40 is cooperable so as to produce a shear cut. The inclination and position of the lower blade 39 is such that when the downwardly movable blade 40 is ad-

vanced toward and over this lower blade, the lower blade is pushed back against the pressure exerted by the springs 59, and as the movable blade 40 is withdrawn from the plane of movement of the lower blade 39, the springs 58 quickly return this latter blade 39 preparatory to the making of a subsequent cut. The movement of the blade 40 in a downward direction, besides severing the tubular ribbon 31, also causes the flexible end of the stripper plate 38 to deflect slightly toward the blade 39 during downward movement of the blade 40 and to strip the stock therefrom during return movement of this blade. The gripping jaw 45 which is oscillatable upon a supporting pivot cylinder 69, is movable with the carriage 41, and the lower jaw plate 48 is adapted to engage the end of the plate 38 when the carriage is advanced to gripping position. When the carriage 41 is thus disposed in gripping position, the jaw plate 48 will have pushed the plate 38 beneath the fixed reaction plate 37, and the jaw 45 then provides an anvil or reaction block for the corrugated plate portion 47 against which the pressure exerted by the crimping plunger 46 may be applied.

The upper knife 40 is movable into active or cutting position by means of mechanism such as shown in Figs. 8 and 9, which is actuated by forward movement of the carriage 41. This mechanism comprises a lever 100, swingably suspended from a fixed pivot 101 and having a laterally projecting pin 102 adapted to coact with one arm of a bell-crank 103; a spring 104 connecting the other arm of the bell-crank 103 with the swinging end of the lever 100 so as to constantly urge the pin 102 toward the upper bell-crank arm; an upper bell-crank lever 105 from one arm of which the movable knife 40 is suspended, and which is swingably mounted on a fixed pin 106; a connection 107 connecting the other arm of the lever 105 with the lower arm of the bell-crank 103; and a spring 108 having one end attached to a medial portion of the connection 107 and its opposite end secured to the stationary frame bracket 58. The lever 100 is adapted to be engaged by the outwardly projecting end of the carriage shaft 80 when the carriage 41 is moved forwardly, so as to cause the pin 102 to contact the bell-crank 103 and to thereby lower the knife 40 into cutting position as shown in Fig. 9, and when the pin 80 is carried past the tip of this lever 100, the spring 108 immediately becomes effective to elevate the knife 40 and to return the actuating mechanism to the position shown in Fig. 8. During subsequent return movement of the carriage 41, the knife 40 will not be displaced, since the advancing pin 80 will then ride along the inclined face of the lever 100 and will swing this lever and the pin 102 thereon away from the bell-crank 103 until the pin 80 has been carried past the lever tip, whereupon the spring 104 will again return the lever 100 and pin 102 to the position shown in Fig. 8.

The crimpler 46 is vertically slidable in grooves formed in the opposite sides of the frame 25, and has its ends connected by means of a link 61, to the swinging ends of arms 62 which are pivotally supported by pins 63 secured to the frame 25, and springs 64 coacting with the medial portions of these arms 62 tend to urge the same upwardly at all times and thus tend to elevate the crimpler 46. One or both of the arms 62 may be provided with an extension 65 connected by means of a rod 66 with a solenoid 67, and this solenoid is

adapted to be energized so as to positively swing the arms 62 downwardly and to lower the crimpler 46, by means of an electric switch 68 which may be carried by one of the side bars 51 and which is operable to energize the solenoid when the handle 49 is swung forwardly to the position shown in Fig. 1.

The vertically reciprocable crimpler 46 has its upper end provided with a bracket 69 forming a transverse abutment 70, and the tucker or folding member 44 is carried by an arm 71 oscillatable upon a pivot 72 and having an extension 73 which is cooperable with the abutment 70. With this assemblage, downward movement of the crimpler 46 will cause the abutment 70 to engage the extension 73 and will thereby swing the tucking member 44 out of the path of movement of the crimpler 46. In order to prevent the tucker from returning to lowermost position immediately when the crimpler is elevated, the pivot 72 is provided at one end with a laterally deflectable arm 74 as shown in Figs. 1, 2 and 6. This arm 74 is adapted to be engaged by a pin 75 carried by the handle 49, when the tucker or member 44 is elevated by the crimpler 46, and when the handle 49 has been moved forwardly to its extreme position so that the pin 75 engages a stop plate 76 secured to the carriage 41. When the crimpler 46 is elevated, the arm 74 engages the pin 75 and the tucker will be held in elevated position as shown in Fig. 2 by the handle 49 which is shown in dash lines in this figure. However, when a pull is exerted on the handle 49, the pin 75 will be withdrawn and the arm 74 is then released and the tucking member 44 is free to drop to its lowermost position.

The gripper jaw or member 45 which performs the dual function of folding the ends of the successive bag assemblages and of subsequently gripping the ends of the bags so as to permit feeding of the stock, is operable by means of a bell-crank 71 secured to the pivot cylinder 60 and having spaced projections 78, 79. The projection 78 is engageable with the lower portion of the handle 49 somewhat above the handle pivot 80, so as to cause the jaw member 45 to move toward the resilient gripper plate 48, and it is to be noted that as the pull on the handle is increased, the gripping force exerted by the jaw member 45 against the jaw plate 48 will also be increased. The projection 79 on the bell crank 71 is adapted to engage a cam 81 secured to one of the guide rails 42, so as to elevate the jaw member 45 when the handle 49 and carriage 41 are moved forwardly, and if the handle 49 is in the position shown in Fig. 1 and this handle is pulled rearwardly to cause the jaw member 45 to grip the block 48, then the projection 79 will be elevated so as not to contact the cam 81. The handle 49 is also provided at its upper end with slotted extensions 82 which are engageable with the bars 51 so as to elevate these bars by causing them to swing about their pivots 54 as the handle 49 is swung forwardly about its lower pivot pin 80, but when the handle is swung rearwardly the extensions 82 permit the bars 51 to drop slightly and thereby permit the seaming roller 33 to engage the tube of stock during advancement of the ribbon 31. An elongated tension spring 84 connects the cylinder 60 with the pin 75 and tends at all times to elevate the gripping member 45.

In order to permit the operator of the machine to properly position printed or decorative mat-

ter which has been applied to the ribbon 31, with respect to the successive bags, we have provided special mechanism operable by means of a lever 109 for bodily shifting the side bars 51 and stops 50 longitudinally of the machine. This mechanism comprises the lever 109 which is pivotally suspended from a pin 110 secured to the frame 25; a lower bell-crank 111 suspended from a fixed pivot 112 and having one end connected to the lever 109 by means of a connection 113; and an upper bell-crank 114 swingably mounted upon the pivot pin 54 and having one arm pivotally attached to one of the side bars 51 while its other arm is connected to the other arm of the lower bell-crank 111 by means of a connecting rod 115. This assemblage is obviously such, that by shifting the lever 109 in either direction, the position of the stops 50 and side bars 51 may be shifted longitudinally of the machine and without displacing the stops 50 relative to the bars 51, thereby permitting slight bodily displacement of the successive bags 52 with respect to the cutting knives 39, 40 for the purpose of properly centering or positioning the printed or decorative matter on the bags.

The normal use of the improved machine while exploiting our present improved method of making bags, is best illustrated in the diagrams of Figs. 17 to 23 inclusive, wherein the various elements which perform the successive steps of the method are shown somewhat diagrammatically, and in these figures the mechanism is viewed in a direction corresponding to that of Figs. 1 to 9 inclusive. When the machine is in condition for normal use, the supply roll 21 should be mounted in the bearings 26 and the ribbon 31 should be disposed in contact with the rollers 29, 30 and should be disposed with its medial portion beneath the former plate 32 so as to provide a tubular ribbon with overlapping edge portions, beneath the folding rollers 31' and the longitudinal crimping roller 33. The stops 50 should be fixed to the side bars 51 at the proper positions so as to produce bags 52 of the desired length, and the roller 33 and crimping member 46 should be properly heated so as to enable these elements to heat the material sufficiently to cause fusion of the coatings at the crimped areas. The use of the machine to form the several types of bags 52, 52' is essentially the same, except that a tucker for forming the accordion pleats 93 of the bag 52' should be provided, and the width of the bags will be dependent upon the width of the former plate 32.

Referring to Figs. 17 to 23 inclusive, Fig. 17 shows the cutting and end sealing assemblage just after a bag has been completed and is about to be severed from the ribbon 31, the upper knife 40 being shown approaching the lower knife 39, and the tucking and gripping elements being remote from the cutting zone with the jaw 45 and plate 48 approaching this zone. With the knife 40 thus approaching the knife 39, the tucking member 44 is located above the corrugated portion 47 of the former plate 32, and the crimpler 46 is held in elevated position by the spring 64. The tube has been longitudinally seamed by application of the roller 33 during a previous forward advancement of the ribbon stock, and the jaw member 45 is elevated as shown.

When the upper blade 40 is advanced downwardly as shown in Fig. 18 by continued forward movement of the carriage 41, it cooperates with the lower blade 39 to shear the previously completed bag 52 from the stock ribbon 31. During

this shearing operation, the inclined lower edge of the downwardly moving knife 40 contacts with the inclined rear edge of the lower knife 39 at approximately one point only and this contact 5 point advances laterally across the plane of cutting until the severance has been completed, thus producing a clean shear cut. Due to the inclination of the rear cutting edge of the knife 39 this knife is forced forwardly against the springs 59, 10 and the advancement of the knife 40 also causes the flexible end portion of the stripper plate 38 to ride upwardly along the cutting side of the knife 40 and thereby positively prevents the end of the tube 31 from sticking to the cutting edge. The tucker 44 and gripping jaw 45 remain in substantially the same relative positions as in Fig. 17 except that the jaw 45 has been advanced toward the plane of cutting with the carriage 41. The next step in the method is shown in Fig. 19 wherein the upper knife 40 has been elevated away from the lower knife 39, and the gripping plate 48 and jaw 45 have been moved into closer proximity to the cut end of the stock tube. The gripping jaw 45 is still elevated but is about to be swung into contact with the plate 48 by virtue 20 of the engagement of the roller 79 with the cam 81 during forward movement of the carriage 41, and the jaw 45 is thereafter lowered as shown in Fig. 20 to cause it to ride beneath the overhanging end portion 88 of the tubular ribbon 31, thus slightly elevating the end portion 88. As the roller 79 passes beyond the cam 81, and the continued forward movement of the handle 49 proceeds, the pin 75 engages the stop plate 76 and the handle 49 swings forwardly about its lower pivot 83 to the position shown in dash lines in Fig. 2.

This forward swinging of the handle 49 after the movement of the carriage 41 has been arrested causes the spring 84 to swing the bell-crank 77 and to elevate the jaw 45 as indicated in Fig. 21, and the jaw 45 then becomes active to fold the portion 88 over the temporarily fixed tucking member 44 as clearly illustrated in Fig. 21. When the handle 49 has been swung forwardly to the extreme extent, it operates the switch 68 to energize the solenoid 67, and this energization causes the solenoid 67 to swing the arms 62 downwardly against the action of the spring 64. The downward swinging of the arms 62 simultaneously causes the tucking member 44 to be withdrawn from the path of movement of the crimpler, and causes the crimpler 46 to lower to the position shown in Fig. 22. The crimpler 46 is then free to perform the crimping and final sealing operation at the end of the tube, and the jaw 45 is approaching the plate 48. It is to be noted that when the final crimping operation is being performed as in Fig. 22, the bag is not sharply folded along the line 89, and the plate 45 provides a reaction anvil for the crimping plunger and corrugated plate portion 47.

As soon as a crimping operation has been completed, the operator pulls rearwardly on the handle 49, thereby immediately actuating the switch 68 in the opposite direction and de-energizing the solenoid 67. The springs 64 then become effective to elevate the arms 62 and to thereby withdraw the crimpler 46. The upward movement of the crimpler 46 causes the abutment 70 to move upwardly and thereby permits the tucking member 44 to return to its lowermost position. The rearward swing of the handle 49 also causes the jaw 45 to swing downwardly and to engage the adjacent portion of the fold 88 and to clamp this

portion against the plate 48, as illustrated in Fig. 23. As the pull on the handle 49 is continued, the folded end of the tube will be tightly gripped by the jaw 45 and the jaw plate 48, and as the carriage 41 is pulled rearwardly, the tubular bag stock is advanced along the former plate 32. During this advancement, the roller 33 is lowered against the overlapped portions of the stock by the lowering of the side bars 51, and the longitudinal seam 87 is thus formed simultaneously with the advancing movement of the stock. When the handle projections 82 engage the limit stops 50, there has been sufficient advancement of the stock to produce a bag of the desired length, and the operation of the carriage may then be reversed to perform a similar cycle of operations. The completed bags 52 which are severed from the continuous ribbon of stock may be dropped upon the floor and loosely stacked upon each other, and may be withdrawn as needed, and it will be apparent that the lengths of the bags may be quickly varied by merely adjusting the stops 50.

During the application of the roller 33 and crimper 46, these elements by virtue of their formation produce the crimping, and the heat applied simultaneously with this crimping produces fusion of the surface coatings at the crimped areas. It will be noted that during the formation of the bottom seal, the folded portion 88 is attached only to the rear wall 86 of the bag, and is not attached to the front wall, thereby making maximum storage space for commodity available within the bag. While adhesive may be applied to the crimped areas in addition to the heating, it has been found that the heating alone will produce bags 52 which are airtight and which can be distended under considerable pressure without bursting and without permitting escape of air from the interior of the bags. The crimped and fused seals are preferably formed on one side of the bag, but the folding and crimping of the lower seal may obviously be applied to the side of the bag opposite to that having the crimped seam 87. The bags 52 may be produced with straight cut lower ends and without having one wall project beyond the other, and the improved adjusting mechanism which is operable by the lever 109, will obviously permit the operator to readily properly position printed or decorative matter on the successive bags. The improved machine and method of producing these bags will also permit a user of small quantities to produce superior bags in a most economical manner and as needed, and such user will always be assured of a supply of fresh bags wherein sharply folded edges are eliminated. The bag forming unit has proven highly successful in actual use, and can be readily manipulated by a novice to produce bags of various types.

It should be understood that it is not desired to limit this invention to the precise steps of the method or to the exact details of construction herein shown and described, for various modifications within the scope of the claims, may occur to persons skilled in the art.

We claim:

1. In combination, a table, means for folding

the edge portions of a sheet of material being advanced along said table into overlapped position and for joining said edge portions to form a flat tube, a pair of members movable toward each other longitudinally of the tube and extending thereacross, one of said members being cooperable with one wall of the tube some distance from its free end and the other being simultaneously cooperable with the other wall to fold the free end of said walls over one of the walls, and means for fusing the folded end areas to said one wall and to each other.

2. In combination, means for folding the edge portions of an advancing sheet of material over each other and for joining said edge portions to form a flat tube, an oscillatory folding member cooperable with the end of the tube while at rest to fold said end over the upper wall of the tube, means for swinging said folding member out of the fold, means for attaching the folded areas to the upper tube wall and to each other to seal said tube end, a former plate confined within said sealed tube for preventing attachment of said tube walls to each other adjacent to the fold line during said end sealing, and means for withdrawing the end sealed tube portion away from said plate.

3. In combination, means for folding the edge portions of an advancing sheet of material over each other and for joining said edge portions to form a flat tube, a single oscillatory bar forming a fold line retaining means cooperable with the end of the tube, means cooperating with said fold line retaining means to fold said end over said bar and the upper wall of the tube, means for moving said fold line retaining means out of the fold, means for sealing the folded area to the upper tube wall to seal the tube end.

4. In combination, in table, means for folding the edge portion of a sheet of material being advanced along the said table into overlapped position and for joining said edge portions to form a flat tube, an oscillatory fold line retaining member cooperable with the end of the tube, means cooperating with said fold line retaining member to fold said end over said fold line retaining member and the upper wall of the tube, means for moving said fold line retaining member out of the fold, means for attaching the folded areas to the upper tube wall and to each other to seal said tube end, a former plate confined within said sealed tube for preventing attachment of said tube walls to each other adjacent to the fold line during said end sealing, and gripping means for gripping and withdrawing the end sealed portion away from said place.

5. In combination, a table, a former plate, means for folding the edge portions of a sheet of material being advanced along said former plate into overlapped position and for joining said end portion to forming flat tube, a fold line retaining bar extending across said former and said tube, reciprocating means for folding the free ends of said walls over said fold line retaining bar and for withdrawing the end sealed portion away from said former plate.
